(57) **CLAIM**

The ornamental design for a sex toy suction cup platform, as shown and described.

DESCRIPTION

FIG. 1 is a perspective elevated view of the top side of the sex toy suction cup platform of my claimed design;

FIG. 2 is a front view of the sex toy suction cup platform of FIG. 1;

FIG. 3 is a back view of the sex toy suction cup platform of FIG. 1;

FIG. 4 is a top side view of the sex toy suction cup platform of FIG. 1;

FIG. 5 is a bottom side view of the sex toy suction cup platform of FIG. 1;

FIG. 6 is a left side view of the sex toy suction cup platform of FIG. 1;

FIG. 7 is a right side view of the sex toy suction cup platform of FIG. 1;

FIG. 8 is a perspective elevated view of the bottom side of the sex toy suction cup platform of FIG. 1; and,

FIG. 9 is another perspective elevated view of the bottom side of the sex toy suction cup platform of FIG. 1, showing the presence of a pair of straps.

The sex toy suction cup platform is shown with a symbolic break in its length within FIGS. 1-5 and FIGS. 8 and 9. The appearance of any portion of the article between the break lines forms no part of the claimed design. The broken lines shown on the bottom side of the sex toy suction cup platform in FIG. 5, FIG. 8, and FIG. 9 form no part of the claimed design. In addition, the broken lines showing a pair of straps in FIG. 9 illustrate environmental structures and form no part of the claimed design.
